UNITED STATES PATENT OFFICE.

FRANK P. DOOLEY, OF CHICAGO, ILLINOIS.

WIRE MATTRESS.

1,268,939.

Specification of Letters Patent. Patented June 11, 1918.

Application filed January 14, 1918. Serial No. 211,816.

To all whom it may concern:

Be it known that I, FRANK P. DOOLEY, citizen of the United States, residing at Chicago, in the county of Cook and State of Illinois, have invented a certain new and useful Improvement in Wire Mattresses, of which the following is a full, clear, concise, and exact description.

My invention relates to wire mattresses of a construction employing a rectangular frame, a plurality of coiled springs disposed perpendicularly to the plane of the frame and arranged in spaced apart rows that extend longitudinally of the frame and which 10 springs are also arranged in rows that extend transversely of the frame, end coils of the springs being substantially in the plane of the frame, and substantially parallel pairs of tie rods margining opposite sides 15 of the spaces between parallel rows of 20 springs and secured at their ends to opposite sides of said frame.

By means of my invention I have dispensed with other tie rods that hitherto have 25 been employed at right angles to the aforesaid tie rods. I accomplish this result by forming the tie rods of each pair with loops 30 that extend across from one row of springs to the adjacent row of springs, each loop having its base and bight respectively in 35 hinge engagement with adjacent sides of the top coils of the two adjacent springs in adjacent rows, the top coil of one of these two adjacent springs being disposed between the base of one loop and the bight of the 40 companion loop, and through which bight the other loop passes, the base of said companion loop passing through the top coil of the other of these two springs, said loops 45 having formations for engaging the top coils of these two springs to prevent material approach or separation thereof whereby the rows of springs margined by the tie rods are maintained substantially parallel.

45 I will explain my invention more fully by reference to the accompanying drawings showing the preferred embodiment thereof and in which Figure 1 is a plan view of a wire mattress constructed in accordance 50 with the invention, parts of the structure being removed as there is not sufficient space to illustrate a mattress with a full complement of coiled springs; Fig. 2 is a view on line 2-2 of Fig. 1; Fig. 3 is a perspective 55 view illustrating the manner in which the adjacent sides of the top coils of springs are

maintained in assembly; Fig. 4 is a perspective view illustrating the formation of a loop in one tie rod; Fig. 5 is a perspective view illustrating the formation of a loop in another tie rod; and Fig. 6 is a view on line 6-6 of Fig. 3.

Like parts are indicated by similar characters of reference throughout the different figures.

The wire mattress illustrated includes a rectangular frame 1. Coiled springs 2 are arranged in one row, coiled springs 3 are arranged in a row parallel to the row that contains the springs 2 and coiled springs 4 are arranged in a row parallel to the other rows of springs. These rows of springs extend longitudinally of the frame. The springs 2, 3 and 4 of the different rows are also arranged in rows that extend transversely of the frame. These coiled springs are disposed perpendicularly to the plane of the frame, end coils of the springs being substantially in such plane. Substantially parallel pairs of tie rods 6, 7 margin opposite sides of the spaces between the rows that contain the springs 2, springs 3 and springs 4. These tie rods are secured at their ends to opposite sides of the frame 1 preferably by being wrapped around these opposite sides as indicated at 6¹, 7¹. The tie rods 6 are shown as being formed with loops 8 that extend across from one row of springs (the row having springs 3 for example) to the adjacent row of springs (the row having the springs 2 for example), the base and bight of each loop 8 being respectively in hinge engagement with adjacent sides of the top coils of the two adjacent springs in adjacent rows. The bight 8¹ of each loop 8 is bent toward the plane of such loop to insure the maintenance of its hinge engagement with the coil end engaged by this bight. Each loop 8 has shoulder formations 8² near its base, the base parts 8³ of each loop 8 being preferably substantially parallel with the main portion of the loop that extends between the rows of springs. The top coil of a spring has hinge engagement with a loop 8 at the corners formed by the parts 8², 8³ of such loop. The shoulders 8² cooperate with the bights 8¹ to prevent the coil ends engaged by the base and bight of each loop 8 from approaching to a material extent. The tie rods 7 are shown as being formed with loops 9 that extend across from one row of springs (the row having springs

3 for example) to the adjacent row of springs (the row having the springs 2 for example), the base and bight of each loop 9 being respectively in hinged engagement with adjacent sides of the top coils of two adjacent springs in adjacent rows. The top coil of one of these two adjacent springs is disposed between the base 8³ of loop 8 and the bight 9¹ of loop 9, the loop 8 passing through the bight 9¹. The base of the loop 9 passes through the top coil with which this base is in hinge engagement, this loop serving to prevent material separation of the two loop coils with which it is in hinge engagement owing to the manner in which its base is engaged with one spring coil and its bight is engaged with the other spring coils.

Side stringers 10 have loops 10¹ by which the longitudinal side rows of coiled springs are anchored to the longitudinal sides of the frame.

Having thus described my invention I claim as new and desire to secure by Letters Patent the following:—

A wire mattress including a rectangular frame; a plurality of coiled springs disposed perpendicularly to the plane of the frame and arranged in spaced apart rows that extend longitudinally of the frame and

which springs are also arranged in rows that extend transversely of the frame, end coils of the springs being substantially in the plane of the frame; and substantially parallel pairs of tie rods margining opposite sides of the spaces between parallel rows of springs and secured at their ends to opposite sides of said frame, the tie rods of each pair being formed with loops that extend across from one row of springs to the adjacent row of springs, each loop having its base and bight respectively in hinge engagement with adjacent sides of the top coils of the two adjacent springs in adjacent rows, the top coil of one of these two adjacent springs being disposed between the base of one loop and the bight of the companion loop, and through which bight the other loop passes, the base of said companion loop passing through the top coil of the other of these two springs, said loops having formations for engaging the top coils of these two springs to prevent material approach or separation thereof whereby the rows of springs margined by the tie rods are maintained substantially parallel.

In witness whereof, I hereunto subscribe my name this 11th day of December, A. D. 1917.

FRANK P. DOOLEY.
